UNITED STATES PATENT OFFICE.

CECIL R. CARLETON, OF BROCKTON, MASSACHUSETTS, ASSIGNOR TO BROCKTON STAY COMPANY, OF BROCKTON, MASSACHUSETTS, A CORPORATION OF MASSACHUSETTS.

FINISHING WELT.

Application filed June 9, 1927. Serial No. 197,577.

This invention aims to provide an improved finishing welt or binding for concealing tacks or other fastening devices.

In the accompanying drawings is shown an illustrative embodiment of the invention, wherein:

Fig. 1 is a plan view of a portion of the welt;

Fig. 2 is a cross-section of the same; and

Fig. 3 is a cross-section of a slightly modified form of the welt.

In the particular embodiment of the invention selected for purposes of illustration and shown in the drawings, the welt comprises a body 1 formed from a piece of suitable sheet material which may be of a color to match or to contrast with the upholstering or covering of the article to which the welt is to be applied.

The body 1 of the welt is formed from a piece or strip of material of predetermined length and width having opposite marginal or edge portions 2 and 3 folded inwardly over the top of the main part of the welt body 15 herein numbered 7. Within the folds formed by the folding of said edge portions, fillers 4 are inserted which may, for example, be composed of paper cords, although the invention is not confined to such material, nor to the particular shape of fillers shown.

The marginal portion 2, at least in the form shown in Fig. 2, is wide enough, when folded over and upon the body portion 7, to extend nearly across the upper face of said portion 35 7, terminating just inside of an edge bead 5 formed by folding the other marginal portion 3 over its filler 4. The marginal portion 2 may be secured to the upper face of the portion 7 in any appropriate manner, as for example by cement, and as herein shown also by stitches 6 extending longitudinally of the welt in close proximity to the inner side of an edge bead 12 formed along the opposite edge of the welt by the marginal portion 2 and its filler 4.

The portion 3 is treated somewhat differently from the portion 2 to the extent that following its aforesaid inward folding over its filler cord 4, the free edge 8 is turned under 50 and back toward the folded edge approximately to the filler 4, thereby completely concealing the raw edge 14 of the material and presenting to view a neatly finished edge 10 just inside said edge bead 5. The raw edge 55 14 of the part 3 terminates approximately in

alignment with the free edge 16 of the upper 60 ply of the marginal portion 2, and both of these edges terminate approximately at the inner side of the filler cord 4.

A second strip of material, indicated generally at 18, may be composed of any suitable material and of appropriate color, for example like that forming the body 1 or contrasting therewith. The material of this strip is folded near its middle at 20 and herein 65 encloses between its plies 22 and 24 an appropriately or as herein shown a convexly shaped filler 26 which latter, together with the covering strip enclosing it, constitutes a center bead 28 for the welt. The plies 22 and 24 of the second mentioned strip, after being folded, are brought together on the opposite side of the filler 26 from the fold 20 and are herein inserted between the plies 2 and 7 on the under side and the two plies 8 and 14 on 70 the upper side, desirably until the edges 30 and 32 respectively thereof substantially engage the filler 4, or at least align with the aforementioned edges 14 and 16 of the parts 2 and 3.

The plies of both strips, namely, the plies 8, 14, 22, 24, 2 and 7 are desirably all secured together by a row of stitches 34 or other securing means extending lengthwise of the welt between the finished edge 10 and the bead 85 5 and these stitches constitute a hinge for the flap or center bead 28.

The finished edge 10 of said turned marginal portion 3 projects beyond the stitches 34 partially over the center bead 28, and being 90 of double thickness it is caused to exert downward pressure upon said center bead due to the tension placed upon the plies 8 and 14 by said stitches 34, the tension whereof is sufficient to draw said several plies firmly together and form the hollow 36 between said center bead 28 and the edge bead 5. This pressure is of material importance in pressing the center flap or bead 28 downwardly against the upper surface of the central portion of 95 the welt body between the edge beads 5 and 12, so that after said center bead has been raised and the tacks or fastening devices, shown herein at 38, have been driven through the body portion of the welt and into the material to which the welt is attached, said center bead or flap will of itself return to its normal fastener-concealing position, as clearly indicated in Fig. 2.

In Fig. 3 a slightly modified form of welt 110

is shown, wherein the marginal portion 2 terminates at 40 slightly within the row of stitches 6 instead of extending across to the stitches 34. In this way a slight depression 5 42 is provided to receive the heads of the tacks 44, permitting the center bead 28 to lie more firmly against and conceal the stitches 6.

In both forms of welt disclosed, it is apparent that the face of the welt along which 10 the edge beads 5 and 12 of the center bead 28 are arranged, is by reason of the relative arrangements of said beads at least when the welt is properly attached to the body of the vehicle or whatever object the welt is to be 15 used upon, to exclude moisture from beneath said beads or from the face of the body of the welt through which the welt securing or fastening means 38 or 44 are driven, thus preventing the rusting of said fastening elements, and also preventing the rotting of the 20 under layers of material composing the welt. For example, assuming the welt to be secured in the position shown in Fig. 1 with the bead 5 at the top a convex surface of said bead 5 25 will shed the water or dust over the flap 10 to the convex surface of the center bead 28, while the center bead by overlying the outer portion 2 of the material forming the lower bead 12 by extending upwardly beneath the 30 center bead 28 will shed the moisture from said lower bead, and thereby prevent its working in beneath said lower bead.

The invention is not limited to the particular embodiment shown.

35 Claims:

1. A finishing welt comprising a strip of material having opposite edges folded inwardly, a filler at each edge of said strip enclosed in each of said inturned portions, the 40 inner edge of one of said inturned edges being turned under and outwardly forming a double thick edge, a second strip of different material folded double to form a flap, and having its free edges inserted between the 45 said double thick edge of the first mentioned strip and the body thereof, and a row of stitches arranged longitudinally of the inner edge of the filler, through the two thicknesses of said doubled edge, also the free edges of 50 said second flap and through the body of the first strip to form a hinge for said flap, said doubled edge, said folded double flap and said filler enclosing portions cooperating to form overlapping moisture shedding portions for the face of the welt.

55 2. A finishing welt comprising a body formed from a piece of material having opposite edges thereof turned inwardly and enclosing fillers at the edges thereof, one of the inturned edges extending substantially across the upper face of said body, the marginal portion of the other inturned edge being folded under toward and adjacent its filler and forming a stiffener for said edge, a 60 flap formed from a separate piece of mate-

rial doubled and having its edge inserted between the turned under edge of the first mentioned strip and the body portion thereof, and stitches extending through all of the plies of both of said pieces of material and constituting a hinge for said flap, said inturned edges and flap overlapping one another and forming moisture shedding portions from the direction of at least one side of the welt.

75 3. A finishing welt comprising a body formed from a piece of material having opposite edges thereof turned inwardly, one of said inturned edges extending toward the opposite edge of the welt and forming an upper 80 ply for said body, a filler element enclosed in the folded edge thereof, a row of stitches along the inner edge of said filler element securing the two thicknesses of said folded edge together over said filler element, the other inturned edge being folded under to form a finished inner edge, a filler element enclosed between the folds at the other edge of said welt, a second piece of material doubled along one edge to form 85 a two-ply flap, a filler element arranged between said plies at the folded edge thereof, the free edges of said plies being inserted between the finished edge portion of said body and the base portion of said body 90 and stitches extending through all the plies of said body and said flap along inside of the second mentioned filler element and constituting a hinge for said flap, said inturned edges and said two-ply flap being arranged in 95 overlapping relation one to another to form moisture and dust excluding means from the direction of one side of the welt.

100 4. A finishing welt comprising a body formed from a strip of material having opposite marginal portions thereof turned inwardly and enclosing filler cords at opposite edges of the body, one of said inturned portions forming an upper ply for said body, the other inturned portion being folded under 105 to form a finished inner edge, a second piece of material doubled along one edge to form a two-ply flap, a filler element arranged between said plies and forming a center bead 110 for the welt, said flap being inserted between the plies of said body on the one side and the plies of said finished edge on the other side, and stitches adjacent said finished edge inside 115 the marginal bead at that side of the welt extending through said flap and adjacent portions of the body and constituting a hinge 120 for the flap, said inturned portions and said filled flap being arranged in overlapping relation one to another to form means for excluding moisture from the direction of one 125 side of the welt.

130 5. A finishing welt comprising a body formed from a piece of material having opposite marginal portions thereof turned inwardly, fillers enclosed within the folds of

said inturned portions and forming beads at opposite edges of said body, means to secure one of the inturned marginal portions to the body by stitches arranged inside of its bead, 5 the free edge of the other inturned portion being turned under to form a finished double thick lip, a second piece of material doubled transversely to form a two-ply flap, a 10 filler arranged between said plies adjacent the folded edge thereof and forming a center bead for the welt, the free edges of said second piece of material being inserted beneath said double thick lip and stitches extending through said double thick lip, through the 15 free edges of said flap and through the under body of said welt and forming a hinge for said flap, the materials forming said finished edge, said two-ply filled flap and the remaining inturned marginal portions being arranged 20 in overlapping relation one with another to exclude from one direction moisture from between said overlapping elements.

6. A finishing welt comprising a body formed from a piece of material having opposite 25 marginal portions thereof turned inwardly, fillers enclosed within the folds of said inturned portions and forming beads at opposite edges of said body, the free edge of one of said marginal inturned portions being turned under to form a double thick finishing 30 lip, a second piece of material doubled transversely along one edge to form a two-ply flap, a filler arranged between said plies adjacent said doubled edge and forming a center bead 35 for the welt, and stitches extending through the double finishing lip of said inturned marginal portions, through the free edges of said flap and through the under body of said welt and forming a hinge for said flap, said 40 stitches being arranged close to the inner edge of the adjacent edge bead and close to the corresponding edge of said center bead whereby the double thick finished lip of said

inturned portion will be caused to exert downward pressure upon said center bead to 45 retain the latter in contact with the body of the welt between said edge beads, said doubled finishing edge and said two-ply filled flap overlapping adjacent portions of the 50 welt to exclude moisture driven against the welt from the direction of one side thereof.

7. A finishing welt comprising a body, an edge bead arranged along the lower edge of said body having a covering extending upwardly against the upper face of said body, 55 a center bead arranged against said covering and secured along its upper side only to the welt body, a second bead arranged along the upper edge of said welt body and having a double thick lip overlying the secured edge 60 of said center bead, said center bead and said double thick lip respectively overlapping in the same direction as the hinged edge of said center bead and the upper edge of said upwardly extending covering portion of the 65 body to exclude moisture and dust from the face of the welt.

8. A finishing welt comprising a body, an edge bead arranged along one edge of said body, the covering of said edge bead 70 having a part turned back over the top of said body, a center bead overlying the turned back edge of said edge bead and hingedly secured to said body along the edge of the center bead remote from said edge bead, the 75 margin of said body opposite to said edge being turned back over and secured with the hinged edge of said center bead to said body and constituting a water-excluding covering for said center bead, said center bead serving 80 as a water-excluding covering for said edge bead.

In testimony whereof, I have signed my name to this specification.
